UNITED STATES PATENT OFFICE.

CHARLES RADIGUER, OF ST.-DENIS, FRANCE, ASSIGNOR TO THE SOCIETE ANONYME DES
ETABLISSEMENTS DELAUNAY-BELLEVILLE, OF ST.-DENIS, FRANCE, A CORPORATION
OF FRANCE.

DEVICE FOR EXHAUSTING THE MOTIVE FLUID FROM SELF-PROPELLED TORPEDOES.

1,261,851.

Specification of Letters Patent.

Patented Apr. 9, 1918.

Application filed June 21, 1915. Serial No. 35,292.

To all whom it may concern:

Be it known that I, CHARLES RADIGUER, citizen of the French Republic, residing at St.-Denis, Department of the Seine, in France, have invented certain new and useful Improvements in New Devices for Exhausting the Motive Fluid from Self-Propelled Torpedoes; and I do hereby declare the following to be a full, clear, and exact description of the invention, such as will enable others skilled in the art to which it appertains to make and use the same.

The invention relates to a new device for exhausting the motive fluid from self-propelled torpedoes. The motive fluid is generally composed of burnt gases and steam, the volume of which it is necessary to reduce in order not to create a counter-pressure having a high value which would interfere with the proper utilization of the energy of the fluid. The device embodying the invention, effects this diminution in volume by canalizing the exhaust gases of the turbine in tubes located in a compartment 25 of the torpedo, accessible from the water side. The gases being strongly cooled by passing through the tubes which act as a kind of surface condensers, they are recovered in a fluid-tight compartment communicating with the hollow tube controlling the propellers, through which the said gases are exhausted in the known manner.

According to the invention, the fluid-tight compartment wherein the tubes acting as condensers, open, is provided with a pump intended to expel the condensed products of the motive fluid. Finally, in the case where it is necessary to impart an impulse to the motive fluid, cooled in the manner hereinbefore described, through the inner 40 end of the concentric shafts controlling the propellers, the motive fluid tube condensers will assume the shape of coils with a view to elongating the path of this fluid in the cooling medium.

This device has considerable advantages of those hitherto in use. The cooling element of which use is made, has an infinite capacity and its circulation is insured without the least expenditure in energy. Moreover, the canalization of the hot gases at their outlet, in fluid-tight compartments, permits of obviating the deteriorating effect they have on the members with which

they come into contact. Finally, an economy is realized in the power requisite for the injection of water at the outlet of the motive fluid, this water having the drawback that it increased the volume and the weight of the exhaust products.

In the accompanying drawing:—

Figure 1 is a vertical section, partly in elevation, of a portion of a torpedo constructed in accordance with the present invention; and

Fig. 2 is a similar view illustrating a modification of the invention.

In the constructional form illustrated in Fig. 1, the motive fluid coming from the generator, penetrates the distribution chamber B through the conduit A. Thence suitably expanded by the nozzles C, it acts on the turbine D which through the medium of toothed gearing (not shown) controls the shaft end F connected with the shaft G 70 which transmits the movement to the propellers.

In the plate H inclosed by the turbine D and the plate J, a certain number of pipes I are provided, and serve for the exhaust 80 of the motive fluid. The compartment K in which these tubes I are located, freely communicates with the exterior through various orifices N formed in the hull. When the torpedo is submerged, water entering 85 through the orifices N invades the compartment K and surrounds the pipes I. It will be readily understood that the motive fluid is subjected to an energetic cooling action 90 inside these tubes.

The cooled fluid penetrates subsequently a fluid-tight compartment P and is drawn in by a bladed wheel R integral with the driving shaft, which forces the said fluid into the hollow shaft G for exhausting in a rearward direction. A pump Q drawing in at the lower part of the reservoir, rejects externally the condensed products; it may be readily controlled by means of an eccentric keyed on the driving shaft.

In the constructional form illustrated in Fig. 2, it has been assumed that the torpedo under consideration is one in which the two propellers are driven in opposite directions by two concentric hollow shafts. In this 105 case it is advisable to bring the exhaust fluid to the end itself of the hollow inner shaft G. This shaft is driven through the medium of

a pinion T keyed thereupon, and the introduction of the gases must be effected on the side of the pinion T opposite to the second hollow external shaft, so as not to increase the length of the apparatus. In order to insure the continued energetic cooling of the motive fluid, the condensing pipes I are suitably curved so as to lengthen the path of the fluid amidst the cooling medium. The 10 gases then penetrate a fluid-tight compartment P thereby insuring their complete insulation from all the delicate parts of the torpedo.

Having now particularly described and 15 ascertained the nature of my said invention and in what manner the same is to be performed, I declare that what I claim is:—

1. In a turbine-driven torpedo, the combination with a turbine, the hollow exhaust 20 shaft and the compartment located between the extremity of said shaft and the turbine, of a casing communicating with said hollow shaft, at least one pipe located in said compartment for conducting the motive fluid 25 discharged from the turbine to said casing, and means to admit sea-water to said com-

partment to cool said pipes, said pipe being of sufficient length to allow the sea-water admitted to said compartment to cool the exhaust gases passing through said pipe. 30

2. In a motor-driven torpedo, the combination with the motor and with the hollow exhaust shaft, of a casing surrounding the extremity of said shaft, means to conduct the motive fluid exhausted from said motor to 35 said casing, and means to discharge the condensed portion of the motive fluid from said casing.

3. In a motor-driven torpedo, the combination with the motor and with the hollow 40 exhaust shaft, of a casing surrounding the extremity of said shaft, means to conduct the motive fluid exhausted from said motor to said casing, and a pump for discharging the condensed portion of the motive fluid from 45 said casing.

In testimony whereof I affix my signature, in presence of two witnesses.

CHARLES RADIGUER.
